UNITED STATES PATENT OFFICE

159,595

BOTTLE CARRIER

Marvin Wayne Bowersox, Arkansas City, Kans.

Application April 14, 1948, Serial No. 145,715

Term of patent 14 years

(Cl. D58—5)

To all whom it may concern:

Be it known that I, Marvin Wayne Bowersox, a citizen of the United States, residing at Arkansas City, in the county of Cowley and State of Kansas, have invented a new, original, and ornamental Design for a Bottle Carrier, of which the following is a specification, reference being had to the accompanying drawing, forming part thereof.

The figure is a perspective view of a bottle carrier, showing my new design.

The side and end of the carrier not shown are substantially the same in appearance as the side and end illustrated.

I claim:

The ornamental design for a bottle carrier, as shown and described.

MARVIN WAYNE BOWERSOX.
